VERTICALLY POLARIZED ANTENNA

Marvel W. Scheldorf, Palos Heights, Ill., assignor to Andrew Corporation, a corporation of Illinois

Application March 8, 1951, Serial No. 214,537

5 Claims. (Cl. 343—905)

The present invention relates to a vertically polarized antenna, and more particularly to such an antenna adapted for VHF operation.

In the past it has been common to provide vertical polarization by antennas of the coaxial type. Particularly for mobile communication service it has been customary to stack concentric cylinders over a supporting mast structure. In the past it has been found that at times coaxial antennas did not produce the transmission characteristics desired. It has also been found that the ground plane antenna likewise at times did not produce the desired transmission characteristics.

The coaxial antenna in one form consists of a vertical quarter wave-length extension of the inner conductor of the transmission line plus a quarter wave-length cylinder over the outer conductor of that line connected at the upper end and free at the bottom to form what is commonly known as a skirt.

The ground plane antenna consisting of a vertical quarter wave-length extension of the inner conductor of the transmission line and a half wave-length diameter ground plane fastened to the end of the outer conductor of that line in a horizontal plane is not susceptible of modification to employ stacking. A number of attempts have been made to solve the vertically polarized stacking problem. It would seem that the predominant cause for their failure is that they employ the concentric cylinder principle. These cylinders must have considerable clearance from the mast for electrical isolation, and hence present large wind loading areas. This requires a large mast diameter, which is bulky and consequently the entire assembly is unreasonably bulky. Such an arrangement furthermore requires feed lines to be brought up through the mast which makes service of the junctions difficult or impossible.

It has been found that one of the most annoying difficulties of both the ground plane antenna and coaxial antennas is the tendency to couple power to the mast, with corresponding sensitivity to surrounding objects and height above the ground. It, therefore, would be desirable to provide an improved antenna structure not subject to certain of these difficulties.

It is, therefore, an object of the present invention to provide an improved vertically polarized antenna having a substantially circular horizontal pattern.

A further object of the present invention is to provide an improved vertically polarized antenna having a high power gain.

Still another object of the present invention is to provide an improved vertically polarized antenna which has negligible coupling to the supporting mast.

A still further object of the present invention is to provide an improved antenna requiring a minimum number of feed points.

Still another object of the present invention is to provide a vertically polarized antenna having a minimum wind load.

Other and further objects of the present invention sub-

2

sequently will become apparent by reference to the following description taken in conjunction with the accompanying drawing wherein:

Figure 1 is a representation of an antenna constructed in accordance with the principles of the present invention;

Figure 2 is a diagrammatic representation of an arrangement for providing a minimum number of feed points for the radiating elements shown in the antenna of Figure 1;

Figure 3 is a side view of one of the radiating elements;

Figure 4 is a diagrammatic top view of the antenna arrangement illustrated in Figure 1; and

Figures 5 and 6 are graphical representations illustrating certain radiation characteristic patterns of the antenna.

In Figure 1 there is shown a supporting mast 11 which carries a plurality of radiating elements 12 through 19 arranged in equal numbers on opposite sides of the mast 11 in a stepped or staggered relation. Each of the radiating elements 12 to 19 is a folded dipole.

In the development of this antenna it was found that a single folded dipole radiating element mounted on a mast was comparatively free from coupling to the mast, but did not in of itself provide a circular horizontal radiation pattern. The use of a pair of dipole elements arranged on opposite sides of the mast provided an arrangement producing the desired circular horizontal pattern without many of the disadvantages encountered in other types of antennas, such as the ground plane antenna and the various forms of coaxial antennas. From an arrangement employing two folded dipole elements on a mast there naturally was developed a folded dipole element array of the stacked variety illustrated in Figure 1.

In order to supply energy to a stacked arrangement, such as shown in Figure 1, there is employed a harness

arrangement diagrammatically represented in Figure 2. Such an arrangement is employed to reduce the number of junctions without affecting the performance of the antenna to any appreciable extent. Therefore, pairs of elements with half wave-length transmission lines are fed at one junction of each pair.

A single transmission line joins the dipoles 12, 13, 16 and 17. This vertical transmission line 21 at its upper extremity is connected to the dipole element 12. At a distance such as .932 half wave-length

there is provided a junction which is connected to the dipole element 16 (.932 being the relative velocity of propagation in transmission line 21). From that junction to the junction connected to the dipole element 13 the distance is 1.068 half wave-length. The distance from the junction to element 13 to the dipole element 17 again

is .932 half wave-length. A similar junction vertical transmission line 22 interconnects the dipole elements 14, 15, 18 and 19. The two vertical junction transmission lines 21 and 22 are interconnected by a spiral junction transmission line 23 arranged on the other side of the mast.

The center of the spiral section 23 is connected to the main feed transmission line 24 which is on the same side of the mast. In one embodiment the two vertical junction transmission lines, such as the transmission lines 21 and 22, had an impedance value of 51.5 ohms. The spiral junction transmission line had an impedance value of

63.8 ohms which was joined to the main feed transmission line having an impedance of 51.5 ohms. Thus at each T junction there is a one to two impedance transformer so that standing wave ratios in the feed transmission lines are the same as for the lines being fed.

The arrangement illustrated in Figure 2 has the advantage of keeping the main feed transmission line and spiral junction transmission line away from the elements thereby to prevent unbalances and disturbances in the radiation pattern. Such an arrangement furthermore has certain physical advantages in that there is no obstruction to the end seal units,

which support the dipole elements, and the junction with

the main feed transmission line is at a position where the line is easily brought down the mast.

Figure 3 illustrates one of the dipole radiating elements which is formed of a plurality of rods or tubes 26, 27 and 28. The rod 27 is connected to the rod 26 at one end by a strap or bar 29. The other rod 28 is connected to the rod 26 by a strap or bar 31. One of the rods such as the rod 27 at its other end is connected to a conductive member 32 which engages a stud 33 arranged coaxially in an insulator 34. The insulator 34 is partially surrounded by a shield 35 connected to one end of the dipole rod 28.

If the elements shown in Figure 3 when mounted on a mast 11, such as shown in Figure 1, were viewed from the top of the mast, the arrangement would be similar to that shown in Figure 4. In that figure the top of the mast 11 is shown as being a large circle. Tangent to the mast are a plurality of shields and insulating members 35 carrying at their outer extremities the dipole elements which include the rods 26 and 27. The dipole elements are connected through the conductive studs 33 to the harness arrangement shown in Figure 2. This is diagrammatically represented in Figure 4 by the application of the reference character 21 to the line element extending between four dipole supporting assemblies.

In Figure 5 there is shown a horizontal radiation pattern which is representative of patterns obtained over a band of frequencies from 148 to 162 megacycles. In the center of this diagram there is represented by a cross hatched circle the support mast 11 which carries the vertical feed line 24 and has radiating dipole elements arranged on opposite sides of the mast 11.

Figure 6 shows the radiation pattern of the antenna in the plane of the feed line.

The resultant antenna structure is one in which there is no substantial coupling to the mast. This is true in the stacked or array arrangement shown in Figure 1, and in the arrangement employing only two radiating elements mounted on opposite sides of the support mast. The central support structure, however, has one other advantage. It provides a vertical polarized antenna which readily permits mounting a beacon or another antenna above it. Likewise a lightning rod may be added to the top of the antenna support without disturbing the operation of the antenna.

While at the present time no completely satisfactory explanation for the isolation of the antenna has been developed, it may be assumed that the fact that heavy standing waves of transmission line current in the folded ends of the elements, oppose one another, the mast current is consequently low. The specific structure described, does not require a return path for transmission line currents, such as are found necessary in all other arrangements. The radiation currents in the elements are additive at the folded ends but the magnitudes relatively approach zero, so there would be little coupling from this portion of the element.

While for the purpose of illustrating and describing the present invention a certain preferred embodiment has been shown in the drawing, it is to be understood that the invention is not to be limited thereby, since such variations in the physical embodiment are contemplated as may be commensurate with the spirit and scope of the invention set forth in the accompanying claims.

I claim as my invention:

1. A multi-element antenna comprising a mast supporting an even number of folded dipole elements in two vertical planes, said elements being located on opposite sides of said mast in staggered relation to each other and in close proximity to said mast, and a coaxial transmission line extending upwardly along said mast, a plurality of vertical transmission lines extending along said mast and each being connected to one half of said dipole elements,

and a sinuous transmission line extending between said vertical transmission lines and said first transmission line.

5 2. A multi-element antenna comprising a mast supporting an even number of folded dipole elements in two vertical planes, said elements being located on opposite sides of said mast in staggered linear relation to each other and in close proximity to said mast, and a coaxial transmission line extending upward along and behind said mast, a plurality of vertical transmission lines extending along the front of said mast, each of said vertical transmission lines being connected to certain dipole elements on opposite sides of said mast, each of said vertical transmission lines having junctions for pairs of said dipole elements at half wave length distance, and a sinuous coaxial transmission line extending between said vertical transmission lines and said first transmission line.

10 3. A multi-element antenna comprising a mast supporting an even number of folded dipole elements, said elements being located on opposite sides of said mast in staggered linear relation to each other, a coaxial transmission line extending upwardly along said mast, a plurality of coaxial vertical transmission lines extending along said mast and each being connected to one-half of said dipole elements, each of said dipole elements having one end connected to the inner conductor of said coaxial transmission line and the other end connected to the outer conductor of said coaxial transmission line, and a sinuous transmission line extending between said vertical transmission lines and said first transmission line.

15 4. A multi-element antenna comprising a mast supporting an even number of dipole elements in two vertical planes, said elements being located on opposite sides of said mast in staggered relation to each other and in close proximity to said mast, each dipole having one element thereof connected to ground, and a coaxial transmission line extending upwardly along said mast, a plurality of vertical transmission lines extending along said mast and each being connected to one-half of said dipole elements, and a sinuous transmission line extending between said vertical transmission lines and said first transmission line, said first coaxial transmission line and said plurality of vertical transmission lines having like impedance characteristic values.

20 5. A multi-element antenna comprising a vertical mast supporting an even number of dipole elements in two vertical planes located on opposite sides of said mast, said elements being arranged in staggered linear relation to each other and in close proximity to said mast, each dipole element having one element thereof connected to ground, and a coaxial transmission line extending along and behind said mast, a plurality of vertical transmission lines extending along the front of said mast, each of said vertical transmission lines being connected to certain dipole elements on opposite sides of said mast, said first coaxial transmission line and said plurality of vertical transmission lines having like characteristic impedance values, each of said vertical transmission lines having junctions for pairs of said dipole elements at half wave length distance, and a sinuous coaxial transmission line extending between said vertical transmission lines and said first transmission line.
